UNITED STATES PATENT OFFICE.

CARL A. ERICKSON, OF BURWELL, NEBRASKA.

PRINTING-MACHINE.

1,275,410.

Specification of Letters Patent. Patented Aug. 13, 1918.

Application filed July 24, 1916. Serial No. 111,042.

To all whom it may concern:

Be it known that I, CARL A. ERICKSON, a citizen of the United States, residing at Burwell, in the county of Garfield and State 5 of Nebraska, have invented certain new and useful Improvements in Printing-Machines, of which the following is a specification.

This invention relates to electric printing machines.

10 The object of my invention is to provide an electric printing machine for printing pictures of any size from films and glass negatives with or without means for leaving a white margin on any size picture printed 15 by the machine.

With the above and other objects in view, the present invention consists in the combination and arrangement of parts herein-after more fully described, illustrated in the 20 accompanying drawings, and particularly pointed out in the appended claims, it being understood that changes may be made in the form, size, proportion and minor details without departing from the spirit or sacrific- 25 ing any of the advantages of the invention.

In the drawings:—

Figure 1 is a central vertical section through the cabinet complete.

Fig. 2 is a plan view.

30 Fig. 3 is a detail perspective of the triangular masking plate.

Fig. 4 is a detail perspective of one of the straight side masking plates.

In the drawings, a suitable cabinet 1 is 35 provided carrying at the lower portion thereof a receptacle 2 for the reception of the electric light bulbs 3. The smaller central bulb is red and is adapted to furnish light at all times, while the remaining lights are 40 the ordinary white lights which are adapted to be controlled by mechanism hereafter described.

The receptacle 2 is spaced from the cabinet at two sides therof to allow for ventilation. 45 Side reflectors 4 of any ordinary type are provided and these reflectors extend from the top plate 5 of the cabinet 1 downwardly within the receptacle 2 in a direction at an angle to the vertical. This construction provides the light chamber 6.

An opening 7 is provided in the top plate 5 through which the light from the chamber 6 is adapted to pass to print the pictures. In the top plate 5, two grooves 8 are cut and 55 in these grooves, blocks 9 carrying straight mask plates 10, are adapted to slide. The

mask plates 10 extend across the opening 7. At one corner of the top plate 5 another groove 11 is cut and in this groove, a block 12 carrying an angular mask plate 13, is 60 also adapted to slide. By adjusting the two straight mask plates 10 and the angle mask plate 13 with relation to each other the opening 7 may be made smaller or larger to enable various size pictures to be printed and 65 to provide a white border of various sizes on the edge of the paper.

On two sides of the opening 7, two guides 10^a and 10^b are located. Guide 10^a is fastened at each of its ends to the corresponding edge of the top plate 5 while guide 10^b has one end bearing in a block 10^c which holds a spring 10^d. This spring normally pushes the guide 10^b into engagement with a notch 10^e provided in guide 10^a thus re- 75 silently holding the two guides 10^a and 10^b together. The guides 10^a and 10^b are adapted to form guides for the paper and the film or negative which is clamped and prevented from accidentally slipping by the 80 guide 10^b.

A cover plate 14 is adapted to close the opening 7 after the paper to be printed upon has been placed over the said opening. This cover plate has two rods 15 extending from 85 one edge thereof and the free ends of these rods are adapted to be received into the elongated openings provided by two staples 16 in the top plate 5, thus providing hinges upon which the said cover plate 14 may be swung. 90 By having the openings in the staples 16 elongated the cover plate 14 will always lie flat upon the paper placed over the opening 7. A metal strip 17 is pivoted to one corner of the cover plate 14 and its free end can be 95 swung to any position on the cover plate.

The metal strip 17 provides a bearing portion for a lever 18 pivoted to the top plate 5 and slidably attached by means of the bracket 19 to the cover plate 14. This lever 100 is adapted to engage the metal strip 17 at any position of the latter on the cover plate 14.

Pivoted to one edge of the top plate 5 is a bar 20 carrying an operating lever 21 and 105 an auxiliary lever 22. The operating lever 21 is connected by a strap 23 to the cover plate 14 and is adapted to engage a bearing 24 rigidly attached to the lever 18. An extension 25 is carried by the lever 21 and a 110 suitable contact member 26 is attached to the extension and insulated therefrom. This

contact member 26 is adapted to engage a pair of contact members 27 attached to, but insulated from, the cabinet 1 which contact members 27 form the terminals of the circuit of the electric lights 3. This circuit is shown diagrammatically in Fig. 1. A circuit maker and breaker, to be hereafter described, is shown diagrammatically at 45 in Fig. 1.

10 From the above it will be seen that the operating lever 21, the lever 18, the metal strip 17, and the cover plate 14 are all indirectly attached together, and that by reason of the strip 17 being swingingly mounted the pressure applied to the lever 21 can be applied to any part of the cover plate 14 through the instrumentality of the said strip 17 and the lever 18.

15 The operation of my invention is as follows:—The mask plates 10 and 13 being adjusted to provide the right sized opening, the paper or film to be printed upon is placed over the said opening and under the guides 10^a and 10^b, the desired distance to 20 provide the desired border on the paper. The lever 21 is then swung to the position shown in Fig. 1, and the cover plate 14 thus located over the paper to be operated upon. The metal strip 17 is then swung to the 25 position on the cover plate at which it is desired to apply the pressure. This being done the lever 21 is pressed downwardly and through the lever 18 and the strip 17, pressure is applied to the cover plate 14. 30 At the same time the contacts 26 and 27 have been brought together, thus closing the circuit of the electric lights. When the printing has been completed, the lever 21 is raised carrying with it the rest of the 35 parts, and the contact between 26 and 27 is broken, thus breaking the circuit of the lights and permitting access to the paper which has been printed, and upon which a white margin has been left.

40 45 What I claim is:—

1. In an electric printing machine, a cabinet provided with an opening, a mask plate slidably mounted along each of two sides of the opening and located at right angles to each other, and a slidably mounted angular mask plate coöperating with the two before-mentioned mask plates to vary the size of the opening and to provide a marginal edge on the paper to be printed.

2. In an electric printing machine, a cabinet provided with an opening, a groove extending along each of two sides of the opening and located at right angles to each other, a pair of mask plates each having a block secured to one end thereof, said blocks being received within said grooves whereby

the mask plates are slidably mounted, and a slidably mounted angular mask plate coöperating with the two before-mentioned mask plates to vary the size of the opening and to provide a marginal edge on the paper to be printed.

3. In an electric printing machine, a cabinet provided with an opening, a mask plate slidably mounted along each of two sides of the opening and located at right angles to each other, a diagonally extending groove formed at one corner of the opening, an angular mask plate, a block secured to the mask plate and sliding in said groove whereby said angular mask plate can be adjusted to coöperate with the two before-mentioned mask plates to vary the size of the opening and to provide a marginal edge on the paper to be printed.

4. In an electric printing machine, a cabinet provided with an opening, a mask plate slidably mounted along each of two sides of the opening, a slidably mounted angular mask plate coöperating with the two before-mentioned mask plates to vary the size of the opening, and a guide bar extending along each of two sides of the opening whereby a white margin of any size can be provided on the edge of the paper to be printed.

5. In a printing machine, a cabinet provided with an opening, two intersecting mask plates slideable over said opening and another slidably mounted mask plate coöperating with said intersecting mask plates to vary the size of the opening and to provide a marginal edge on the paper to be printed.

6. In a printing machine, a cabinet provided with an opening, two intersecting mask plates slideable over said opening, and a slidably mounted angular shaped mask plate coöperating with the aforesaid mask plates to vary the size of the opening and to provide a marginal edge on the paper to be printed.

7. In a printing machine, a cabinet provided with an opening, two intersecting mask plates movable over said opening, and a slidably mounted Y-shaped mask plate coöperating with the aforesaid mask plates to vary the size of the opening and to provide a marginal edge on the paper to be printed.

In testimony whereof I affix my signature in the presence of two witnesses.

CARL A. ERICKSON.
